CLAIM

The ornamental design for a water bottle, as shown, and described.

DESCRIPTION

FIG. 1 is a perspective view of a water bottle, showing my new design;

FIG. 2 is a side view thereof;

FIG. 3 is a top view thereof;

FIG. 4 is a bottom view thereof; and,

FIG. 5 is an exploded perspective view thereof.

The broken lines depict environment and form no part of the claimed design.
